UNITED STATES PATENT OFFICE

137,983

DESIGN FOR A MATCH BOOK

George C. Macdonald, Boston, Mass.

Application March 17, 1944, Serial No. 112,943

Term of patent 14 years

(Cl. D48—29)

To all whom it may concern:

Be it known that I, George C. Macdonald, a citizen of the United States, residing at Boston, in the county of Suffolk and State of Massachusetts, have invented a new, original, and ornamental Design for a Match Book, of which the following is a specification, reference being had to the accompanying drawing, forming a part thereof.

In the drawing,

Fig. 1 is a front view of a closed match book showing my new design;

Fig. 2 is a rear view thereof;

Fig. 3 is a front view of the opened match book of Fig. 1; and

Fig. 4 is an edge view thereof looking to the left of Fig. 1.

I claim:

The ornamental design for a match book, substantially as shown.

GEORGE C. MACDONALD.
